UNITED STATES PATENT OFFICE.

LESLIE V. GRANTIER, OF ROYAL OAK, MICHIGAN, ASSIGNOR TO MCCORD RADIATOR & MFG. CO., OF DETROIT, MICHIGAN, A CORPORATION OF MAINE.

ENGINE-COOLING SYSTEM.

Application filed November 26, 1926. Serial No. 150,706.

This invention relates to vapor or steam cooling systems for internal combustion engines as used on motor vehicles.

The object of the invention is to provide an improved venting means for the condenser or cooler of the system so as to insure the condensing of practically all steam entering the vent from the condenser and thus avoid the escape and loss of steam at the vent as heretofore.

The invention consists further in the matters hereinafter described and claimed.

In the accompanying drawings—

Fig. 1 is a side view (more or less diagrammatic) of an automobile engine assembly equipped with a vapor cooling system having a condenser or cooler with vent means of my invention;

Fig. 2 is a front view of the condenser to show that it resembles the customary automobile radiator;

Fig. 3 is an enlarged vertical sectional view through the condenser and showing my improved venting system;

Fig. 4 is a rear view of the upper portion of the condenser to show vent tubes;

Fig. 5 is a vertical section taken on line 5—5 of Fig. 4; and

Fig. 6 is a horizontal sectional view taken on line 6—6 of Fig. 3.

In Fig. 1, 1 indicates the block of an internal combustion engine of the automotive type, and 2 indicates the head clamped on the block over the upper ends of the cylinders 3 therein as in engines of this kind. The block 1 has the usual water jacket chamber 4 about the cylinders and the head has an upwardly extending manifold 5 in direct communication with said chamber and forming a steam collecting space above the same, as shown.

Arranged in front of the block 1 is a condenser or cooler 6 in accordance with the usual automotive power plant design. A conduit 7 connects the upper end of the condenser 6 with the manifold 5 above the water level *a* therein. Below the condenser is a reservoir 8 of a capacity to hold all the water required for the cooling system and sufficient in excess as a reserve supply. A conduit 9 connects the lower end of the condenser 6 with the adjacent end of the reservoir. A force pump 10, preferably driven by the engine, is located at the other end of the reservoir and has its intake con-

nected with the bottom thereof by a conduit 11.

Conduits 12 and 13 extend upward from the pump, and are connected at their lower ends with the discharge and intake, sides, respectively, of said pump. The upper end of the conduit 12 connects with the lower portion of the water jacket 4, while the upper end of the conduit 13 connects with the manifold 5 at the normal water level *a* therein, as shown.

When first putting the cooling system in operation, the reservoir 8 is completely filled with water to about the level *b*, any excess overflowing through the filling neck 70 on top of the reservoir. On first starting the engine, the pump 10 fills the jacket 4 through conduit 12, drawing water for the purpose from the reservoir 8 and lowering the level therein to approximately that indicated by the dotted line *c*. When the jacket fills to the level *a*, all excess water pumped into the jacket through conduit 12 by-passes back to the intake of the pump through conduit 13 which is made larger in diameter than conduit 12 so as to take care of the excess water without allowing it to back up in the manifold 5 or overflow into the condenser 6.

The circulation of water through the jacket 4, conduits 12, 13 and pump 10 continues without passing through either the condenser 6 or the reservoir 8, with the result that the circulated liquid is not subjected to any appreciable cooling action, and its temperature from the heat of the engine cylinders quickly and rapidly rises to the boiling point. This allows the motor to warm up quickly and remain at a substantially constant temperature during operation, irrespective of load, speed or weather conditions. As soon as steam is given off at the level *a*, it rises into the manifold 5 and passes therefrom into the upper end of the condenser 6 where the steam is condensed as it passes downward through the passages in the condenser. A fan 14 is associated with the condenser 6 and is preferably operated by the engine, to draw currents of air through the condenser to condense the steam therein.

The condensed steam flows into the lower end of the condenser and passes therefrom as condensate into the reservoir 8 so as to return to the system and thus allow the cooling liquid to be used over and over again.

without replenishing except at long intervals. So much of the system shown and described forms the subject matter of my co-pending application Serial No. 101,034, filed April 5, 1924.

In said application, I have shown the vent for the condenser exterior thereof and in the form of a relatively short pipe let into the upper side of the conduit 9 connecting the lower portion of the condenser 6 with the reservoir 8. A vent of that character is necessarily small and possesses practically no cooling surface or volume with result that steam may escape to the atmosphere 15 from the condenser and be lost. This especially takes place when the engine is stopped after being under heavy load, at which time the excess heat in the block 1 is given up to the cooling water causing it to continue to boil. The fan 14 is not in operation and there is little cooling of the steam in the condenser 6, which is already at a high temperature due to the interrupted air flow. Steam therefore passes through the condenser without being wholly condensed and escapes at the vent and is entirely lost.

It is the object of my present invention to overcome these difficulties and I do so by providing a venting means having a considerable cooling surface and volume so as to condense substantially all of the steam vapors entering the vent means from the condenser.

The venting means of my present invention may be incorporated directly in the structure of the condenser 6 and I have so shown the same in the accompanying drawings. As shown in Figs. 2 and 3, the condenser 6 may take the form of the customary automobile radiator so as to fit in with the customary automobile design. The condenser has upper and lower chambers or headers 15, 16 and an interposed core 17 of either the tubular or the cellular type, mounted within an outer casing or shell as in radiator design.

The core 17 has a plurality of vertically disposed passages similar in structure and design and suitably spaced apart for the passage of currents of air between them as in automobile radiator practice. These passages are divided into two sets, the passages 18 of one set being far greater in number than those of the other set and extending between and connecting the upper and lower chambers or headers 15, 16. This allows the steam to flow from the upper to the lower header and condense in the passages 18, the condensate collecting in the lower header 16. The passages 18^a of the other set are at the opposite sides of the core and open into the lower header 16 only, the latter being made longer than the upper header for the purpose. The upper ends of the passages 18^a terminate short of

the upper header 15, and there open into expansion chambers 19, 19 built in the core structure at the sides thereof as shown in Fig. 3.

Each chamber 19 has a vent pipe or tube 20 leading out of the same at the rear of the core as shown in Fig. 4. These pipes are preferably inclined upwardly to return any condensate therein to the core and are connected together at the rear of the upper header 15 just below the dummy filling neck 21, with which the upper header 15 is provided in order to give the condenser 16 the full appearance of the customary automobile radiator. One of the pipes 20 opens 80 into the neck 21 and the latter has a cap 22 with a vent opening 23 to the atmosphere as shown in Fig. 5.

As shown in Fig. 6, the vent passages 18^a extend from the front to the rear of the core to the same extent as the steam passages 18. This, coupled with the fact that there are a multiplicity of these vent passages and that they are almost as long as the steam passages provides the vent passages with considerable radiating or cooling surface and expansion space to effect the condensing of practically all steam vapor which enters the vent passages from the lower header 16. Moreover, with the expansion chambers 19 at the upper ends of the vent passages further opportunity is afforded for any steam getting past the vent passages to condense before reaching the atmosphere through the tubes 20, 20 and the neck 21. Furthermore, with the vent passages 18^a located at the opposite sides of the core and out of the direct path of the steam flow through the passages 18, the vent passages 18^a will be at a lower temperature than the steam passages 18, and thus serve to condense substantially all steam entering the same under nearly all operating conditions. Consequently with my invention, substantially, if not all, steam generated during the operation of the system is condensed and returned as condensate to the system without any being lost through the vent as heretofore. Thus with my invention there is very little loss of steam at the vent even under heavy steaming conditions with the result that replenishing of the system with water or cooling liquid is made unnecessary except over long periods.

The details of structure shown and described may be variously changed and modified without departing from the spirit and scope of my invention.

I claim as my invention:

1. In a vapor cooling system for internal combustion engines, the combination with a condenser having a vapor inlet at its upper end and a condensate outlet at its lower end, of vent means incorporated in the structure 130

of the condenser at the opposite sides thereof and extending upwardly along the same from the lower portion of the condenser and having a relatively large radiating surface and volume so as to condense substantially all vapors entering the vent from the condenser to avoid the loss of vapors therefrom.

2. A condenser for vapor cooling systems for internal combustion engines, said condenser having a condensate collecting chamber and vapor passages opening into the same, and vent means for said chamber, said vent means having a relatively large radiating surface and volume so as to condense substantially all vapor entering the vent from the condenser to avoid the loss of vapors therefrom.

3. A condenser for vapor cooling systems for internal combustion engines, said condenser having a condensate collecting chamber and vapor passages opening into the same, and vent means for said chamber, said vent means embodying a multiplicity of passages open at one end to the atmosphere and connected at the opposite end to said chamber, said vent passages being long enough and sufficient in number to condense substantially all vapors entering the same from said chamber.

4. A condenser for vapor cooling systems for internal combustion engines, said condenser having upper and lower vapor receiving and condensate collecting headers, respectively, and a core structure between said headers and having a multiplicity of vertically disposed vapor and vent passages spaced apart for the flow of air currents between them, the vapor passages opening into both headers while the vent passages

open at their upper ends to the atmosphere 40 and at their lower ends into the lower header, said vent passages being similar to and substantially as long as the vapor passages and sufficient in number to condense substantially all vapor entering the same 45 from the lower header.

5. A condenser for vapor cooling systems for internal combustion engines, said condenser having upper and lower vapor receiving and condensate collecting headers, 50 respectively, and a core structure between said headers and having a multiplicity of vertically disposed vapor and vent passages spaced apart for the flow of air currents between them, and expansion chambers in 55 the core structure on the opposite sides thereof and open to the atmosphere, the vapor passages opening into both headers, while the vent passages open at their upper ends into the expansion chambers and at 60 their lower ends into the lower header.

6. A condenser for vapor cooling systems for internal combustion engines, said condenser having a core structure including upper and lower headers and vent and vapor 65 passages between them, expansion chambers in the core structure at the opposite sides thereof and having the upper ends of the vent passages communicating therewith, vent pipes for said chambers, and a tubular 70 neck on the upper header and opening to the atmosphere, said pipes being upwardly inclined and connected together adjacent said neck with one pipe opening into the same.

In testimony whereof I affix my signature this 22 day of November, 1926.

LESLIE V. GRANTIER.
